UNITED STATES PATENT OFFICE.

DWIGHT K. HALL, OF MONTCLAIR, NEW JERSEY, ASSIGNOR TO FRANK A. HALL, OF MONTCLAIR, NEW JERSEY.

BED OR THE LIKE.

1,171,944.

Specification of Letters Patent. Patented Feb. 15, 1916.

Application filed May 11, 1914. Serial No. 837,621.

To all whom it may concern:

Be it known that I, DWIGHT KIMBALL HALL, a citizen of the United States, residing at Montclair, in the county of Essex and State of New Jersey, have invented certain new and useful Improvements in Beds or the like, of which the following is a specification.

This invention relates to certain new and useful improvements in beds, cribs, or the like, in which there is provided a vertically slideable side frame, which when in its uppermost position constitutes with the other side and two end frames, a complete inclosure, and which may be moved to its lowermost position in order to permit of ready access to the bed or crib.

One of the objects of the invention is to provide a structure of this general type in which there is a latch or lock for holding the movable side frame in its uppermost position, which latch is controlled by foot-operating means out of reach of a child within the crib or bed.

Another object is to provide a structure of the kind described in which, when the latch is operated, the movable frame will slide downwardly by gravity, so that it need not be manipulated at all in sending it to its downward position.

Still another object is to provide a form of latch such that it will always return to latching position when the movable side frame is brought to its uppermost position, and further to provide a latching mechanism in which only a portion of the same is moved when the movable side frame is raised to its uppermost position.

Other objects of the invention will appear from the following specification, and the scope of protection contemplated will be indicated in the claims.

In the accompanying drawings, which are to be taken as a part of this specification, and in which I have shown a preferred form of embodiment of the invention as applied to one side of an ordinary bed or crib, Figure 1 is a side elevation, showing the movable parts in one position in full lines and in another position in dotted lines, and Fig. 2 is a detail illustrating the latch, latch-operating means, and the relation thereof to the movable side frame.

Referring to the numerals on the drawings, there are shown at 3, two of the cor-

ner posts of a bed or crib, and it will be understood that there are two more such corner posts on the other side of the structure, and that the other side of the structure may be provided with means similar to what is shown in the drawings. Each of the corner posts may be provided with a caster 4, and the corner posts are connected by means of a side rail 5, as usual. Each corner post is also provided with a guide rod 6 suitably secured thereto as by means of the brackets 7, and there is a side frame 8 which is vertically slideable on these guide rods 6. The side frame 8 comprises upper and lower horizontal rails and vertical connecting rods 9. The ends of each of the horizontal rails are provided with alined apertured lugs 10, through which pass the respective guide rods 6. The guide rods 6 will, of course, be considerably longer than the height of the side frame 8, the guide rods extending from points near the upper ends of the corner posts 3 to points near the lower ends thereof, so that when the side frame 8 is in its uppermost position it will be slightly above the side rail 5 of the bed, as shown in full lines in Fig. 1, and when it is in its lowermost position, indicated by dotted lines in Fig. 1, ready access may be had to the bed by reaching over the upper horizontal rail of the side frame 8. The side frame is held in its uppermost position, shown in full lines in Fig. 1, by means of a pair of members 11. Each one of these members 11 is pivotally secured to a clip member 11', this clip member in turn is arranged to be securely held in position by having one of its ends bent around the horizontal flange of the side frame as shown in Fig. 2. The free end of the pivoted member 11 is upwardly curved to provide a seat for the lower horizontal rail of the side frame 8, and the member 11 is capable of being moved upwardly to the dotted line position of Fig. 2.

Coöoperating with each of the pivoted members 11 is a two-armed wiper 12 which is pivoted on the side rail 5 of the bed. Each wiper 12 has a depending arm 14, and the ends of these depending arms 14 are pivotally connected to a connecting rod 15. The connecting rod 15 is pivoted intermediate its ends, as at 16 to a foot lever 17, which foot lever is pivoted to the side rail 5 of the bed as at 18. It will be evident that

as the foot lever 17 is moved in either direction, as for instance to the position shown in dotted lines in Fig. 1, the wipers 12 will likewise be brought to the positions indicated in dotted lines in that figure, with the result that the pivoted members 11 will be raised up to the position shown in dotted lines in Fig. 2. Before this is done, the side frame 8 will be slightly raised so that its weight will no longer bear upon the members 11, and so that the members 11 may swing freely to the dotted line position of Fig. 2 under the impulse of the wipers 12. The members 11 being held in the dotted line position of Fig. 2, the frame 8 may be permitted to slide vertically downward on the guide rods 6 to the dotted line position of Fig. 1. When it is desired to bring the said frame to its full line position of Fig. 1 again, this is accomplished by returning the foot lever 17 to its full line position shown in Fig. 1, and then raising the side frame to the dotted line position of Fig. 2. The pivoted members 11 have, in the meantime, assumed the full line position of Fig. 1 for the reason that the spring bed bottom, indicated conventionally by dot and dash lines in Fig. 2, presses against the free ends of the pivoted members 11, and tends to displace them from their vertical position to the full line position of Fig. 2. It should be noted that when the side frame is raised the members 11 are the only part of the latch mechanism which is moved, thereby overcoming serious objections in similar constructions in the prior art in which the entire mechanism including the leverage system are adapted to move when the side rail is raised. When in this elevated position if the side frame 8 be now released, it falls into position on the outer ends of the pivoted members 11 as shown in full lines in Fig. 2. It will be understood of course that

the pivoting or hinging of the members 11 is such that they cannot swing downwardly 45 below the level shown in full lines in Fig. 2.

I claim:

1. The combination with a bed structure having a side rail and a frame vertically movable in a plane outside the side rail, of a pivoted member carried by the side rail having its free end movable transversely into and out of the path of travel of said frame, a movable lever mechanism having connection with said side rail and adapted to have frictional engagement with said pivoted member for moving the pivoted member out of the path of the movable frame.

2. The combination with a bed structure having a side rail and a frame vertically movable in a plane outside the side rail, of a pivoted member carried by the side rail having its outer end movable transversely into and out of the path of movement of the frame, a lever pivoted to the side rail, a wiper having frictional engagement with said pivoted member for moving said member out of the path of the frame, said wiper having swinging connection with said lever and said side rail.

3. The combination with a bed structure having a side rail, a frame vertically movable in a plane outside the side rail, a member pivoted to the side rail and having transverse movement into and out of the path of travel of said movable frame, a lever pivoted to the side rail and provided with means for frictionally engaging the member to raise the same out of the path of travel of the frame.

In testimony whereof I affix my signature in presence of two witnesses.

DWIGHT K. HALL
